IGNITER FOR OIL BURNERS

Kemper P. Brace and Franklin H. Wells, South Bend, Ind., assignors to International Engineering Corporation, Chicago, Ill., a corporation of Illinois

Application March 14, 1938, Serial No. 195,770

7 Claims. (Cl. 158—28)

This invention relates to oil burners and similar devices, and more particularly to ignition means therefor.

An object of the invention is to provide a hot-wire ignition device which will vaporize and ignite the fuel with a minimum input of electrical energy. Another object is to so locate the igniter that after ignition is effected the igniter itself will be entirely outside the zone of burning of the fuel and consequently will not be subjected to extremely high temperatures, and so that the electrical connections thereto will not be subjected to high temperatures, and preferably also so that the igniter is shielded from the direct flow of air for combustion. Another and very important object is to provide a very effective form of hot-wire igniter using a relatively small current and which quickly reaches a high temperature when the ignition current is passed therethrough.

The igniter, in the form illustrated in the drawing, comprises a resistance wire wound to form a relatively long small-diameter inner coil encircled by a relatively short large-diameter outer coil, and is arranged in the rear end of an air passage approximately at the center of a porous refractory member to which the fuel is fed, and through which the fuel seeps transversely of a series of such air passages.

Thus initial ignition takes place after the oil has traveled far enough to give time for the igniter to heat up and yet far enough from the bottom of the porous member so that no fuel is lost by dripping from its lower surface before combustion starts. Moreover ignition takes place well behind the zone in which combustion takes place after the burner gets started. Preferably a shield is placed just behind the igniter, to insure turbulence of the fuel-air mixture during ignition, and to shield the igniter from the direct flow of air thereafter.

The above and other objects and features of the invention will be apparent from the following description of the illustrative embodiment shown in the accompanying drawing, in which:

Figure 1 is a central vertical section longitudinally through the burner as it appears when mounted in a furnace; and

Figure 2 is a side elevation, on a larger scale, of the igniter proper.

Tests of hot-wire igniters, for oil burners and the like, have shown that with a given length and size of wire and with a given current input the manner in which the wire is coiled or otherwise arranged has a very great effect on its tem-

perature, and consequently on its effectiveness in igniting the oil. In a single coil the most effective arrangement is in a coil of substantial diameter whose length is approximately equal to its diameter.

We provide such a coil 10, of suitable resistance wire; we find, however, that we can greatly increase its effectiveness by arranging it to encircle a relatively long small-diameter inner coil 12. Preferably the two coils are integral, being 10 wound from the same resistance wire with the outer coil arranged centrally of the inner coil, as shown in Figure 2. Since the inner coil is radiating to a hot outer coil, and receives heat from the outer coil, it as well as the outer coil 15 becomes very hot and is very effective.

The igniter is arranged at the rear end of one of a plurality of air passages 14 through and paralleling the axis of a porous refractory member 16, the igniter being approximately at the 20 center of its rear face. The illustrated porous member 16 is formed with a convex front face and a substantially plane rear face, with the passages 14 paralleling its axis.

Fuel is supplied to the upper part of member 25 16 by means such as a spout 18 having a removable cleanout plug 20 and discharging into one of the upper passages 14. The spout 18 receives oil fuel through a conduit 22, fed by gravity or by a suitable pump, under the control of 30 a fuel valve (not shown) controlled by the usual room thermostat (not shown). The fuel seeps downwardly through the porous structure of member 16, transversely of the passages 14.

The member 16 is secured, by means such as 35 a holding ring 24, in the front end of a generally-cylindrical open-ended carrier 26. The carrier 26 is flanged outwardly at its rear end and secured (by suitable fastenings) to the rear end of a casing 28 formed to be seated in the fuel 40 door or other opening in the side wall of a furnace, a suitable refractory panel 30 closing the remainder of the opening. The front end of the casing is shown conical, so that in a general way it parallels the front face of the member 16. 45 The whole burner is mounted to discharge into the furnace at a slight angle downwardly.

Excess fuel, in the case of ignition failure for example, may drain back through a conduit 32 to operate a suitable float-type safety shut-off 50 switch (not shown).

If desired, the conduit 32 may also be utilized as a housing for an ignition wire 34 connected to a binding screw 36 passing through an insulating bushing 38 to a heavy wire support 40, 55

The support 40 and a similar support 42 grounded on the carrier 26 are welded or otherwise secured to the ends of the resistance wire making up the coils 10-12, and support the igniter as well as supply current thereto when the room thermostat calls for heat.

A shield 44, preferably of mica or other transparent refractory material, may be mounted on the ends of the resistance wire, a short distance 10 behind the rear face of the member 16.

The flow of air through the burner, under the influence of the suction from the chimney of the furnace, is controlled by a glass or other transparent hemi-spherical closure 46 having a 15 central stem 48 adjustably threaded into a nut 50 secured to a diametrically-arranged vertical bar 52 welded at its ends to the flanged rear end of carrier 26.

It will be seen that, when the igniter is first 20 energized, the flow of air through the burner is slow as compared to the flow after the burner is in operation. When the fuel seeps down far enough to reach the passage containing the igniter, the heat therefrom vaporizes and then 25 ignites a small part of the fuel. The air flow through the burner almost immediately reaches such a velocity that the zone of combustion is just in front of the member 16 and in the front ends of the passages 14, leaving the igniter 10-12 30 and its connections 40-42 entirely behind that zone. The shield 44, if used, insures turbulence of the fuel-air mixture about the coils 10-12 during ignition, and also protects the igniter from the direct flow of air after ignition when 35 the flow becomes more rapid.

Since the closure 46 and the shield 44 are transparent, the operation of the igniter and of the burner can conveniently be observed at any time.

40 Except for our improvements in the construction and arrangement of the igniter, the illustrated burner is covered by applications Nos. 145,706 and 195,769, filed respectively June 1, 1937, and March 14, 1938, by Kemper P. Brace, 45 and is not claimed herein.

While one illustrative embodiment has been described in detail, it is not our intention to limit the scope of the invention to that particular embodiment, or otherwise than by the terms of 50 the appended claims.

We claim:

1. An oil burner comprising an open-ended casing adapted to be mounted in an opening in the side wall of a furnace, a porous refractory 55 member supported at the front end of the casing and which is formed with air passages therethrough generally paralleling the axis of the casing, means at the rear end of the casing for varying the air flow through the casing, a hot-wire igniter supported in the rear end of one of said air passages approximately in the central plane of said member and which includes a resistance wire formed to provide a small diameter inner resistance coil encircled by a large diameter outer resistance coil, and means for supplying liquid fuel to said member to seep therethrough transversely of said passages.

2. An oil burner comprising an open-ended casing adapted to be mounted in an opening in the side wall of a furnace, a porous refractory 70 member supported at the front end of the casing and which is formed with air passages there-

through generally paralleling the axis of the casing, means at the rear end of the casing for varying the air flow through the casing, a hot-wire igniter supported in the rear end of one of said air passages which includes a resistance wire 5 formed to provide a small diameter inner resistance coil encircled by a large diameter outer resistance coil, a shield mounted behind said igniter and spaced from the rear side of said member, and means for supplying liquid fuel to 10 said member to seep therethrough transversely of said passages.

3. An oil burner comprising an open-ended casing adapted to be mounted in an opening in the side wall of a furnace, a porous refractory 15 member supported at the front end of the casing and which is formed with air passages therethrough generally paralleling the axis of the casing, means at the rear end of the casing for varying the air flow through the casing, a hot-wire 20 igniter supported in the rear end of one of said air passages, a shield mounted behind said igniter and spaced from the rear side of said member, and means for supplying liquid fuel to said member to seep therethrough transversely of said 25 passages.

4. An oil burner comprising a porous refractory member having a convex front face and a generally plane rear face and formed with air 30 passages therethrough, means to supply liquid fuel to said member to seep through the structure thereof transversely of said air passages, a hot-wire igniter in the rear end of one of the air passages and which consists of a resistance wire formed to provide a relatively small diameter 35 inner coil encircled by a relatively large diameter outer coil, and a shield spaced a short distance behind the igniter opposite the central portion of the rear face of said member.

5. An oil burner comprising a porous refractory member having a convex front face and a generally plane rear face and formed with air 40 passages therethrough, means to supply liquid fuel to said member to seep through the structure thereof transversely of said air passages, a hot-wire igniter in the rear end of one of the air 45 passages, and a shield spaced a short distance behind the igniter opposite the central portion of the rear face of said member.

6. An oil burner comprising a porous refractory member formed with air passages therethrough, means to supply liquid fuel to said member to seep through the structure thereof transversely of said air passages, a hot-wire igniter in the rear end of one of the air 55 passages and which consists of a resistance wire formed to provide a relatively small diameter inner coil encircled by a relatively large diameter outer coil.

7. An oil burner comprising a porous refractory member formed with air passages therethrough, means to supply liquid fuel to said member to seep through the structure thereof transversely of said air passages, a hot-wire igniter in the rear end of one of the air 60 passages and which consists of a resistance wire formed to provide a relatively small diameter inner coil encircled by a relatively large diameter outer coil, and a shield spaced a short distance behind the igniter opposite the central portion of the rear face of 65 said member.
